Attorney

UNITED STATES PATENT OFFICE

CLAUDE W. HOLSTEIN, OF ST. ALBANS, WEST VIRGINIA

FOUNTAIN PEN

Application filed June 4, 1930. Serial No. 459,137.

This invention relates to certain new and useful improvements in fountain pens, and has more particular reference to that type of fountain pen, the barrel of which is 5 adapted to receive therein a cartridge of ink.

A primary object of this invention is therefore to provide a cartridge fountain pen having associated therewith an improved 10 feeder to facilitate puncturing the plug closing one end of the cartridge and at the same time to provide for a smooth and steady feed of ink from the cartridge to the pen point.

A still further object of the invention is 15 to provide a fountain pen of the above mentioned character which is comparatively simple in construction, consists of but relatively few parts, is inexpensive, thoroughly reliable, practical and otherwise well adapted to 20 the purpose designed.

Other objects and advantages of the invention will become apparent during a study of the following description, taken in connection with the accompanying drawings, 25 wherein:

Figure 1 is a longitudinal sectional view taken through my improved fountain pen, certain parts of the cartridge being shown broken away,

30 Figure 2 is a plan view of my improved feeder,

Figure 3 is a sectional view taken through the closure plug of the cartridge.

Referring more in detail to the drawings, 35 it will be seen that my improved fountain pen comprises a suitable barrel 5 internally threaded at one end for threaded reception of the reduced threaded end of a stem stock 6 as at 7. At its opposite end, the barrel 5 is provided with a reduced externally 40 threaded portion for threadedly receiving the internally threaded closure cap 9 as at 8.

A cartridge 11 filled with ink of any desired color or grade is inserted in the barrel 5, and the cartridge 11 is closed at one end, and its open opposite end is normally closed through the medium of a plug 13 formed of rubber or any other suitable material. The closed end of the cartridge 11 50 projects beyond the adjacent end of the bar-

rel 5 to project into the cap 9. The cap 9 is provided internally with a suitable coil spring 12 bearing against said closed end of the cartridge 11 for urging the same forwardly to abut the shoulder portion of the 55 stem stock 6 for retaining the cartridge in place against the barrel.

The plug 13 for closing the open end of the cartridge 11 is as before mentioned formed of rubber or any other suitable material to fit snugly within the open end of the cartridge. Inwardly from said open end, the cartridge 11 is pressed inwardly to provide an internal annular shoulder 16 against which the inner face of the plug 13 60 is adapted to abut for retaining the plug 13 against being pressed too far inwardly of the cartridge 11. The plug 13 is provided with an axial bore 14 normally closed at one end of the plug by a suitable punctur- 65 able area or a disk 15.

My improved feeder is designated by the reference character 17. The feeder 17 on the top thereof is provided with an ink groove 18 extending longitudinally thereof 70 from the forward pointed end of the feeder to a point inwardly from the rear end of the feeder. At said rear end the feeder 17 is provided with a bore 20 inclining downwardly and rearwardly from 75 the inner end of the groove 18.

A feed tube 19 has one end fitting within the groove 20 and the opposite end portion projecting beyond the corresponding end of the feeder 17. Said opposite end portion 80 of the tube 19 is offset and at its free end is beveled to provide a penetrating point 21. Obviously as the cartridge 11 is formed longitudinally of the barrel toward the stock 6, the penetrating point 21 will pierce the 85 disk or penetrable area 15 so that the offset end portion of the tube 19 will extend through the bore 14 to terminate inwardly of the cartridge 11 thus providing a feed 90 passage to the groove 18.

95 From the foregoing then it will be seen that as the pen is disposed in the usual position for writing the ink will be fed from the passage 11 through tube 19 and groove 18 to the pen point 22 which is supported 100

suitably on the feeder 17 between the feeder and pen stock in the usual manner.

Of course, for refilling the pen it is merely necessary to withdraw the emptied cartridge 11 and insert in the barrel 5 a filled cartridge in substitute thereof.

Even though I have herein shown and described the preferred embodiment of my invention, it is to be understood that the same is susceptible to changes fully comprehended by the spirit of the invention as herein described and the scope of my appended claim.

Having thus described my invention, what I claim as new is:

In a fountain pen, a feeder formed of suitable material and adapted to be supported in the stock of the fountain pen, said feeder provided on the top face thereof with an ink groove leading inwardly from the forward end of the feeder to terminate at its inner end inwardly from the rear end of the feeder, said feeder at said rear end having an inclined bore inclining rearwardly from the inner end of said groove to the rear end of the feeder, and a tube having an end portion extending through said bore to terminate at the inner end of said groove, said tube having its opposite end portion extending beyond the corresponding end of said feeder, said tube providing an ink feed leading from the barrel of the pen into said ink groove.

In testimony whereof I affix my signature.

CLAUDE W. HOLSTEIN.
